HYDROLYSIS OF WOOD WITH CONCENTRATED HYDROCHLORIC ACID

Theodor Riehm, Mannheim-Rheinau, Germany, assignor to Deutsche Bergin-Aktiengesellschaft, Mannheim-Rheinau, Germany

Application March 18, 1953, Serial No. 343,103

Claims priority, application Germany March 21, 1952

7 Claims. (Cl. 127—37)

This invention relates to the hydrolysis of cellulosic materials with high concentrated hydrochloric acid.

In the commercially used large scale saccharification of wood and similar materials, a battery of about 14 to 18 diffusors is used, which are connected by a complicated system of pipes for circulating and recycling the various solutions used and obtained in the process. The front diffusors are used for the saccharification proper and the back diffusors serve for recovery of the hydrochloric acid from the residual lignin. This battery process is known as the "Rheinau process"; its output is essentially governed by the charging sequence of the diffusors which cannot be increased beyond about 5 hours per diffusor. Within this time interval, the foremost empty diffusor must be charged with fresh wood in such a way that the wood charged through a hopper provided at the top of the diffusor is continuously moistened with a hydrochloric acid sugar solution. The hydrochloric acid sugar solution is then again withdrawn from the bottom of the diffusor, passed through a cooler to carry away the reaction heat, and recycled to the hopper at the top of the diffusor. After the diffusor has been filled in this way with moistened wood, additional solution is charged and the charge is allowed to stand for a certain time. Subsequently, the finished acid sugar solution ready for withdrawal is displaced from the newly mashed diffusor by the effluent liquid of the succeeding diffusors. Afterwards, additional sugar solution is swept out of this diffusor and employed for mashing and filling a fresh diffusor, which has been emptied in the meantime. In this battery process, the wood remains in the acid for about 50 hours, if only the saccharification battery is considered, and for about 100 hours, if the whole battery including the washing battery is considered.

It has also been proposed to carry out the saccharification in a continuous process in towers, but such methods could not yet be reduced to practice.

It is a principal object of the invention to provide a completely continuous saccharification process, which avoids the drawbacks of the known methods and requires a relatively small reacting zone.

Another object of the invention is to provide a saccharification method, which does not require the use of mechanical elements.

Still another object of the invention is to provide a saccharification process in which the lignin can be washed without objectionable dilution of the bulk of the hydrochloric acid.

In the conventional battery process about 2½ times the amount of the theoretically required high concentrated hydrochloric acid must be employed; because of the unavoidable dilution with water, more than half of this hydrochloric acid amount is withdrawn from the washing battery in the form of an only medium concentrated hydrochloric acid, which has to be again enriched to the original concentration, whereby the water introduced into the acid cycle must be sluiced out with a high consump-

2

tion of thermic energy. It is a further object of the invention to provide a process which needs only the theoretically required amount of high concentrated hydrochloric acid.

5 It is still another object of the invention to provide an apparatus suitable for carrying out the new saccharification process.

According to the invention, a liquid column consisting of defined contiguous zones is caused to travel continuously through the stationary wood, and the zones of the traveling column are maintained stationary by providing the reaction towers with inlets and outlets through which the required liquids are introduced into suitable zones of the traveling liquid column and through which suitable amounts of liquid are withdrawn from other zones, respectively.

In order to ensure an entirely uniform travel of the whole liquid column, wherein the concentration of the various zones remains constant, theoretically an infinite or at least a very large number of inlet and outlets should be provided. I have found, however, that in practice a relatively small number of such inlets and outlets is sufficient. The intermittent advance of the acid flow is balanced by a layer of high concentrated substantially sugar-free hydrochloric acid between the acid sugar solution and the dilute acid, and the change of the direction of flow from the foremost to the next succeeding tower is rendered innocuous by providing a sufficiently prolonged layer of a concentrated sugar solution containing, for instance, about 20 to 25 g. of sugar per 100 cm.³ of solution.

The invention will be explained more in detail with reference to the accompanying drawing, wherein

Fig. 1 is a diagram illustrating the successive operative stages in a saccharification apparatus according to the invention, and

Fig. 2 is a diagrammatical elevation of a tower which is conically tapered at top and bottom and suitable for use in the practice of the invention; the figure illustrates the air and water feed lines for removal of the residual lignin and the draw-off lines for said lignin.

The apparatus consists, for instance, of 4 towers A, B, C, D, each containing 345 liters. The ratio of diameter to height of the towers may be, for instance, 1:10. Each tower is provided at the top with an inlet and at the bottom with an outlet for the passage of the traveling liquid column, and additional uniformly spaced inlets or outlets are distributed over the length of the towers. There may be, for instance, as shown in the drawings, two lateral inlets or outlets which divide the tower in three sections of substantially equal height. All the lines are provided with sieves. The towers are charged, for instance, each with about 81 kg. of prehydrolyzed dried beech wood. The liquid column, divided into zones, flows in the direction of the arrows continuously through the towers.

Wood is charged continuously into the front tower A so as to provide at all times for a wood layer above the liquid surface; the height of the wood layer must be sufficient to prevent escape of hydrochloric acid gas into the atmosphere.

The drawing illustrates the operations and the flow diagrams shortly before the end of each respective operation as follows:

65 Into the last tower D, wash water is fed continuously through *a* in an amount of 33.8 l./h. until 0° hour. At the same time, dilute hydrochloric acid is continuously withdrawn through the lower lateral line at *f*. At the beginning, the concentration of said hydrochloric acid is about 3%; the concentration decreases until the acid contains eventually only 0.5% of HCl. About 11.6 l./h. of dilute hydrochloric acid are drawn off through *f* into

3
the vessel F, and about 9.4 l./h. of about 41 percent hydrochloric acid are introduced over the same time into the top of tower C at b. From the bottom of tower C about 28.2 l./h. of solution pass continuously into the bottom section of tower B, while a corresponding volume of concentrated sugar solution flows from the top of tower B into the collecting tank E. In this way, 61 l. of hydrochloric acid sugar solution have been withdrawn from tower B into the tank E until 0° hour.

During the same time, a suitable quantity of wood has been charged into tower A at a uniform rate of about 6 kg./h. At 0° hour, the lines are switched in the manner shown in the drawing for 5° hour. Otherwise, all the solutions and charges keep flowing continuously at the same rate. During this step, tower A is filled up to the level of the lower lateral line, whereupon again 61 l. of acid sugar solution are withdrawn therethrough into the collecting tank E. The drawing shows the apparatus at the end of this step. At 5° hour, the lines are again switched, without any other changes in the feed and withdrawal of water, acid, sugar solution and wood, respectively. At 10° hour, tower D has been washed acid-free and is shut down. The wash water is then fed into the tower C. The shut down tower D is emptied and newly charged with wood, since in the meantime, tower A has been filled up with dry wood. At 15° hour, the wood layer in tower D has again reached a certain height.

In order to remove the lignin, water is injected into tower D from the bottom through a separate line p, and withdrawn at the top of the tower through a large stoneware valve 1 and a pipe with about an 80 mm. diameter. The rate of flow of the water in the lower section of tower D is slowly increased to about 1.5 cm./sec., calculated on the free cross section of the tower. During this operation, the lignin extends upwardly and partly flows out through the upper conduit. Subsequently, air is slowly added to the affluent water at the bottom of the tower until the ratio of water to air is about 1:1 by volume. In this way, almost the entire lignin is swept out of the tower within a short time. Small amounts of larger lignin particles cannot be carried upwardly in this way without a substantial increase of the injected water and air amounts; they are drawn off through a lower line n without, however, discontinuing the injection of water and air from the bottom before the tower has become free of lignin.

At 15° hour, the apparatus is in the same state as at 0° hour, with the sole difference that the whole saccharification column and the whole washing column have advanced by a full tower length. In the time from 15° hour to 20° hour, the same operations take place as in the time between 0° hour and 5° hour.

The described process results in a complete saccharification of the wood. No washing acid need be drawn off, except the insignificant amounts (calculated as hydrogen chloride) in the form of very dilute hydrochloric acid, which can be used entirely for the prehydrolysis.

In the known battery process, the high heat of wetting had to be carried away by an uneconomic acid cycle through brine coolers; in the process of this invention, said heat remains as a very short heat wave always in front of the displaced sugar solution and is intermittently withdrawn from the apparatus together with said acid sugar solution. In the aforementioned example, only a few liters of the acid-sugar solution, when drawn off through the respective outlets, are heated up to about 35° C., while the rest of said withdrawn acid-sugar solution and the entire other contents of the respective tower have a temperature not substantially exceeding 23° C. As the effluent acid-sugar solution is continuously vaporized immediately after withdrawal, any deterioration of the very heat-sensitive acid-sugar solution is automatically prevented in the new process. This is a great advantage over the battery process where, without the complicated cool-

ing cycle, a whole diffusor volume would be subject to the harmful effect of high temperatures over a prolonged period of time.

The invention may be carried out with a smaller or larger number of towers, e. g. with 3 or 6 towers. I have, however, found that an apparatus comprising 4 towers offers particular advantages for carrying out the invention on a technical scale.

The reaction towers may be conically tapered at the top and bottom, as shown in Fig. 2. The ratio of diameter to height may be 1:4 to 1:10. According to the dimensions of the towers, particularly to their height, up to five or more equally spaced lateral inlets or outlets may be provided. In general, two lateral inlets or outlets have proved to be sufficient and satisfactory.

The invention is preferably carried out in such a way that a plurality of reaction towers is connected in series and that a continuous current of liquid is passed in each tower from the top to the bottom, whereby wash water is fed into the last tower D and about 41% HCl preferably into about the middle of the series, for instance, into tower C; very diluted hydrochloric acid is drawn off preferably from the last third of the series and hydrochloric acid-sugar solution from the first tower A. The hydrochloric acid sugar solution, which may contain about 25 to 50 g. sugar per 100 ccm. of solution, is withdrawn in a volume corresponding to the sugar conversion of the cellulose contained in the wood of one tower. The strongly diluted hydrochloric acid is drawn off in a volume which corresponds to the small amount of HCl, which has traveled towards the end of the tower series as a consequence of the continuous displacement of diffusion and mixing effects, so that a steep acid concentration gradient is maintained in the stationary state. Concentrated hydrochloric acid is admitted in a volume replacing the amount of HCl withdrawn in the hydrochloric acid sugar solution and in the very diluted hydrochloric acid, so as to maintain the hydrochloric acid content of the whole system. Wash water is added in such a volume that a tower newly charged with wood and connected to the series can be filled and the required volume of hydrochloric acid sugar solution can be drawn off, taking into account the aforementioned added and withdrawn amounts of liquid.

The wood is charged into the front tower A continuously at such a rate that it forms above the liquid level a protecting layer of sufficient height to prevent the breakthrough of hydrogen chloride gas into the atmosphere. For removal of the heat of reaction, hydrochloric acid sugar solution is drawn off in a suitable amount through each of the lateral pipes of the foremost tower B which is being filled from the bottom with solution.

The process is carried out in such a way that there is maintained in the foremost part of the tower system a sufficient zone of concentrated acid sugar solution, which extends over 1/2 to 1 tower length, subsequently a sufficient saccharification zone, then a short zone of substantially sugar free high concentrated hydrochloric acid, a subsequent washing zone of sufficient length, characterized by a steep concentration decline, and a zone of substantially acid-free wash water, which zone intermittently increases to a full tower length and advances continuously through the whole wood column. This advance is brought about by effecting the feed and withdrawal of wash water and hydrochloric acid at suitable places of the saccharification and washing system, by advancing in regular intervals the inlet of the acid and the outlet of acid sugar solution by one tower section and the water inlet by a whole tower, and by controlling the rate of flow so that the wood remains 8-30, preferably about 15 hours in the saccharification zone.

In 4 tower systems, the acid is introduced, preferably through two inlets, at a distance of 1 to 2 1/2 tower lengths, preferably 1 1/2 to 2 tower lengths, rearwardly of the liquid surface of the foremost tower; the diluted acid is drawn off at the distance of 1 1/2 to 2 1/2, preferably 2 to 2 1/2

tower lengths rearwardly of said liquid surface, i. e. about $\frac{1}{3}$ — $\frac{1}{2}$ tower length rearwardly of the acid admission. The water feed is switched from the top of the fourth tower at *a* to the top of the third tower at *k* when the first tower is filled to about two thirds, so that there is sufficient time for emptying the last tower without interrupting the continuous charging of the wood.

In the apparatus shown in Fig. 1, each of the four towers is provided with lateral branch pipes serving as inlets or outlets, which divide the tower in 3 sections of about equal extension. *E* is the collecting vessel for the withdrawn sugar solution, and *F* is a collector for the strongly diluted hydrochloric acid obtained by the washing of the lignin, which acid is continuously withdrawn through a lateral outlet of the corresponding tower (*f*, *g*, *h*, *i*, respectively). The concentrated hydrochloric acid feed is advanced from *b* over *c* and *d* to *e*.

In Fig. 2 the devices *m* and *l* are valves for the circulation of sugar solution and hydrochloric acid.

What I claim is:

1. In the hydrolysis of wood with concentrated hydrochloric acid, the steps which comprise providing a plurality of separate stationary columns of lignin-containing prehydrolyzed cellulosic material, said columns being connected in series to form a saccharification unit, introducing continuously concentrated hydrochloric acid containing about 40% by weight of HCl in to said unit to hydrolyze the cellulose to sugar, said concentrated hydrochloric acid forming in said unit a zone of fresh concentrated hydrochloric acid and in front thereof in the direction of flow a zone of acid sugar solution, intermittently withdrawing said acid sugar solution at a point spaced by the length of at least one column from the point of admission of said concentrated hydrochloric acid, introducing continuously water into said unit at a point rearwardly of the admission of said concentrated hydrochloric acid for removing hydrochloric acid from the residual lignin, said water forming a washing zone and in front thereof in the direction of flow a zone of dilute hydrochloric acid, intermittently advancing in the direction of flow the admission of said concentrated hydrochloric acid and said water and the withdrawal of said acid sugar solution, continuously withdrawing a portion of said dilute hydrochloric acid at a point located between the points of admission of said water and of said concentrated hydrochloric acid, and adjusting the admissions and withdrawals of the liquids so as to maintain a substantial equilibrium between the amounts of withdrawn and introduced HCl and a substantially uniform concentration in said zones during their advance through the unit.

2. In the process as defined in claim 1 the step of introducing the concentrated hydrochloric acid in an amount not substantially exceeding the theoretically required amount.

3. In the process as defined in claim 1 the step of charging lignin-containing cellulosic material into the front column at a rate sufficient to maintain a layer of solid material above the surface of liquid, which layer prevents the escape of hydrochloric acid gas into the atmosphere.

4. In the process as defined in claim 1 the step of injecting water into the bottom of a column of residual lignin freed from cellulose and hydrochloric acid so as to loosen said lignin, admixing air to said water, withdrawing said air and water carrying lignin suspended therein from the top of said column, and drawing off the portion of the lignin not suspended laterally from the bottom of the column.

5. In the hydrolysis of wood with concentrated hydrochloric acid, the steps which comprise providing separate successive batches of prehydrolyzed lignin-containing cellulosic material connected in series so as to form a saccharification unit having a first batch, a last batch, and at least one intermediate batch, directing a continuous liquid column through said unit in the direction from the last batch towards the front batch, introducing continuously concentrated hydrochloric acid containing about

40% by weight of HCl into an intermediate batch of said unit to hydrolyze the cellulose to sugar, said concentrated hydrochloric acid forming in said unit a zone of fresh concentrated hydrochloric acid and in front thereof in the direction of flow a zone of acid sugar solution, introducing continuously water to the top of the last batch of the unit for removing hydrochloric acid from the residual lignin, said water forming a washing zone and in front thereof in the direction of flow a zone of dilute hydrochloric acid, advancing the introduction of water to the next preceding batch after said zone of dilute hydrochloric acid has been displaced from said last batch into the next preceding batch, intermittently advancing in the direction of flow the admission of said concentrated hydrochloric acid, continuously withdrawing a portion of said dilute hydrochloric acid at a point located between the points of admission of said water and of said concentrated hydrochloric acid, intermittently advancing said point of withdrawal of dilute hydrochloric acid simultaneously and conforming with the advance of the point of admission of said concentrated hydrochloric acid, intermittently withdrawing acid sugar solution from the front of the liquid column adjusting the admissions and withdrawals of the liquids so as to maintain a substantial equilibrium between the amounts of withdrawn and introduced HCl and a substantially uniform concentration in said zones during their advance through the unit, removing the last batch after the water introduction has been switched to the next preceding batch, providing a batch of fresh prehydrolyzed lignin-containing cellulosic material, making said batch the first batch of said unit and continuing applying the recited sequence of steps to said unit, thereby removing said last batch and replacing said first batch whenever the water introduction has been switched from the last batch to the next preceding batch.

6. A continuous wood saccharification process with concentrated hydrochloric acid containing about 40% by weight of HCl comprising the steps of providing always three complete stationary columns of prehydrolyzed wood while a fourth column of said wood is being built up, said four wood columns being connected in series as a saccharification unit terminating with said fourth column; continuously directing a liquid column through said unit in the direction of said fourth wood column, said liquid column comprising successively in the direction of flow a washing zone, a zone of dilute hydrochloric acid, a zone of said concentrated hydrochloric acid, and a zone of acid sugar solution, said zones constituting in said order about 20%, 20%, 10%, and 50% of the total length of said liquid column, respectively; intermittently withdrawing said acid sugar solution from the front end of the advancing liquid column at a point below the top of said fourth wood column; advancing at predetermined intervals said point of withdrawal conforming to the build up of said fourth wood column; continuously introducing said concentrated hydrochloric acid at a point spaced by the length of about 1 to $2\frac{1}{3}$ wood columns rearwardly of the front end of said liquid column; continuously introducing water to the top of the wood column preceding in the direction of flow of the liquid column that wood column which received the concentrated hydrochloric acid; intermittently advancing the admission of said concentrated hydrochloric acid conforming to the advance of the point of withdrawal of the acid sugar solution; continuously withdrawing a portion of dilute hydrochloric acid at a point located between the points of admission of said water and of said concentrated hydrochloric acid, and advancing said point of withdrawal at predetermined intervals conforming to the advance of the point of introduction of said concentrated hydrochloric acid; adjusting the amount of introduced concentrated hydrochloric acid so as to substantially replace the amount of HCl withdrawn as sugar solution and dilute hydrochloric acid; intermittently removing the wood column which has been passed by said zone of dilute hydro-

chloric acid after the build up of a fourth wood column has been completed, replacing said exhausted wood column by building up a fresh column of prehydrolyzed wood and making said fresh column, while being built up, the fourth column of said saccharification unit; and continuing the flow of said liquid column through said unit while said exhausted wood column is replaced by a column of fresh material.

7. The saccharification process as claimed in claim 6, wherein the points of withdrawal of sugar solution and 10 the points of admission of the concentrated hydrochloric acid are advanced in intervals of about 5 hours by the length of about $\frac{1}{3}$ of a wood column.
